UNITED STATES PATENT OFFICE

140,803

DESIGN FOR AN INTERNAL COMBUSTION ENGINE UNIT

Stanley Z. Siwek and Harry Goldberg, Chicago,
Ill., assignors to H. Goldberg, Chicago, Ill.

Application February 9, 1945, Serial No. 117,851

Term of patent 14 years

(Cl. D77—1)

To all whom it may concern:

Be it known that we, Stanley Z. Siwek and Harry Goldberg, both citizens of the United States, residing at Chicago, in the county of Cook and State of Illinois, have invented a new, original, and ornamental Design for Internal Combustion Engine Unit, of which the following is a specification, reference being had to the accompanying drawings, forming part thereof.

side and one end of an internal combustion engine unit, embodying our new design; and

Figure 2 is a perspective view showing the top, opposite side and other end thereof.

We claim:

The ornamental design for an internal combustion engine unit, substantially as shown.

STANLEY Z. SIWEK.
HARRY GOLDBERG.
